UNITED STATES PATENT OFFICE.

JOHN C. KANE, OF DETROIT, MICHIGAN.

TELEPHONE-RECEIVER.

1,362,008.

Specification of Letters Patent. Patented Dec. 14, 1920.

Application filed October 21, 1919. Serial No. 332,151.

To all whom it may concern:

Be it known that I, JOHN C. KANE, a citizen of the United States, and a resident of Detroit, in the county of Wayne and State of Michigan, have made certain new and useful Improvements in Telephone-receivers, of which the following is a specification.

My invention is an improvement in telephone receivers of the character specially adapted for "radio" work, wherein a diaphragm is provided balanced in the magnetic field between the pole pieces, to reduce the stress and permit the use of a very thin steel diaphragm and a very powerful magnetic field.

A further object is to provide a receiver wherein the vibrations of the coil windings, as well as those produced by the motion of the molecules in the pole pieces, is utilized.

In the drawings:

Figure 1 is a perspective view of the improved receiver in use;

Fig. 2 is a diagrammatic plan view showing the circuit connections;

Fig. 3 is a longitudinal section of the receiver;

Fig. 4 is a section on the line 4—4 of Fig. 3.

In the present embodiment of the invention, two coils 1 and 2 are provided, mounted upon soft iron pole pieces 3 and 4, the said pole pieces being arranged in axial alignment, as shown, with their adjacent ends spaced apart far enough to receive the diaphragm 5 between them.

The diaphragm is held between the sections 6 and 7 of an inclosing shell, the said sections being cup-shaped, and being connected at their adjacent ends by a ring 8 which is threaded on to the sections. Each section 6 and 7 has an internally threaded opening 9 at its outer end, for engaging the adjacent pole piece, each pole piece having a threaded portion beyond the coil for engaging the internally threaded opening.

The binding posts 10 and 11, which are connected with the terminals of the respective coils, extend through openings in the ends of the sections 6 and 7, and are insulated therefrom by tubes 12 and washers 13 of suitable insulating material. As shown in Fig. 3, the bores of the pole pieces 3 and 4 flare at their inner ends toward the dia-

phragm and the diaphragm is firmly held 55 between the sections 6 and 7 of the shell, which incloses the coils.

Nuts 14 are threaded on to the pole pieces outside of the shell sections, and by means of these nuts the pole pieces and the coils 60 may be adjusted toward and from the diaphragm to perfectly balance the same.

The inclosing shell 6—7 is of hard steel permanently magnetized so as to induce positive and negative poles in the interior 65 ends of the pole pieces, and these poles will have their unlike ends adjacent. That is, the two pole pieces will be similarly arranged. The coils are wound to a very high resistance, and they are so arranged that 70 when a current passes through them they oppose each other, that is, the like ends will be adjacent. Now the diaphragm is balanced, and when a current passes through the coils, the balance of the field is shifted, 75 and the diaphragm swept with it. An increase of the field strength will intensify the action of the diaphragm up to saturation of the pole pieces. The pole pieces are slotted to prevent as much as possible eddy 80 currents and by means of the nuts at the outer end, they may be adjusted to get the diaphragm at the critical balance. This diaphragm may be of steel, and of .015 inch.

Flexible tubes 15 extend from the ends of the 85 pole pieces, the said tubes being arranged upon reduced portions 16, at the outer ends of the pole pieces, and each tube 15 has an ear piece 17 at the end remote from the receiver for engaging within the ears of the 90 user. The receiver is supported from the neck by means of a tape or strap 18, whose ends are connected with the shell on either side of the ring 8. Thus the receiver is supported on the chest, and the tubes 15 are 95 of sufficient length to engage the ears without strain.

In use, the receiver is arranged in the line 18 connecting the aerial 19 with the ground in the manner shown in Fig. 2. Lead wires 100 20 connect with the binding post 10 at the ends of the receiver, and a lead wire 21 connects the binding post 12.

The inclosing shell is permanently magnetized so as to induce positive and negative 105 poles in the interior ends of the pole pieces. This magnet entirely inclosing the coil, as it does, performs the very important func-

tion of confining the magnetic field of the coil within the instrument, making for stronger signals.

I claim:—

5. 1. A receiver of the character specified, comprising a pair of alined pole pieces, a coil on each pole piece, a sectional shell inclosing the coils and having openings through which the pole pieces are threaded, a ring connecting the adjacent end of the shell sections and having threaded engagement therewith, a diaphragm held between the shell sections and between the adjacent ends of the pole pieces, and means for adjusting the coils and pole pieces toward and from the diaphragm, said means comprising lock nuts threaded onto the pole pieces outside of the shell sections.
10. 2. A receiver of the character specified, comprising a pair of alined pole pieces, a coil on each pole piece, a sectional shell inclosing the coils and having openings through which the pole pieces are threaded, a ring connecting the adjacent end of the shell sections and having threaded engagement therewith, a diaphragm held between the shell sections and between the adjacent ends of the pole pieces, and means for adjusting the coils and pole pieces toward and from the diaphragm.
15. 3. A receiver of the character specified, comprising a pair of alined pole pieces, a coil on each pole piece, a sectional shell inclosing the coils and having openings through which the pole pieces are threaded, a ring connecting the adjacent ends of the shell sections, a diaphragm held between the shell sections and between the adjacent ends of the pole pieces, and means for adjusting the coils and pole pieces toward and from the diaphragm.
20. 4. A receiver of the character specified, comprising a shell supporting a diaphragm transversely thereof, pole pieces carrying coils adjustably connected with the end of the shell for movement toward and from the diaphragm, said pole pieces having flexible tubes connected with their outer ends and carrying ear pieces.
25. 5. A receiver of the character specified, comprising alined tubular pole pieces, each pole

piece carrying a coil, said coils when electrified having their like ends adjacent; a diaphragm held between adjacent ends of the pole pieces, means for adjusting the pole pieces toward and from the diaphragm, and receiving tubes connected with the pole pieces.

6. A receiver of the character specified comprising a shell supporting a diaphragm transversely thereof, pole pieces adjustably connected with the ends of the shell for movement toward and from the diaphragm, said shell and the pole pieces being permanently magnetized, and the pole pieces having their unlike poles adjacent, coils carried by the pole pieces and adapted to be interposed in electrical circuit in series in such manner that when energized their like poles will be adjacent.

7. A receiver of the character specified comprising a shell supporting a diaphragm transversely thereof, pole pieces connected with the ends of the shell for movement toward and from the diaphragm, said shell and the pole pieces being permanently magnetized, and the pole pieces having their unlike poles adjacent, coils carried by the pole pieces and adapted to be interposed in electrical circuit in series in such manner that when energized their like poles will be adjacent.

8. A receiver of the character specified comprising a shell having a diaphragm supported transversely thereof and having pole pieces at its ends for movement toward and from the shell, a coil on each pole piece, said shell and pole piece being permanently magnetized so that the unlike poles of the pole pieces are adjacent and the coils being arranged so that when energized their like poles will be adjacent.

9. A receiver of the character specified comprising a diaphragm, a pole piece at each face of the diaphragm, a coil carried by each pole piece, said pole pieces being permanently magnetized and having their unlike ends adjacent and the coils being arranged so that when magnetized their like ends will be adjacent.

JOHN C. KANE.
